[57] **CLAIM**

The ornamental design for the four-bin tray, as shown and described.

DESCRIPTION

FIG. 1 is a front elevation of a four-bin tray showing our new design;

FIG. 2 is a top plan view thereof;

FIG. 3 is a rear elevation thereof;

FIG. 4 is a bottom plan view thereof;

FIG. 5 is a right side elevation thereof;

FIG. 6 is a top, front, and left side perspective view thereof; and,

FIG. 7 is a top, front, and left side perspective view showing a state in which the four-bin tray may be used in combination with a printer.

The broken line showing of a printer in FIG. 7 is for illustrative purposes only and forms no part of the claimed design.
